UNITED STATES PATENT OFFICE

2,581,665

ELECTROMAGNETIC OPERATING MECHANISM FOR TYPEWRITERS

Herman Jarmann, Schodack Landing, N. Y.

Application July 30, 1948, Serial No. 41,598

14 Claims. (Cl. 197—19)

1

My invention relates to improvements in electromagnetic operating means for typewriters of commerce.

The primary object of my invention is to provide an electromagnetic mechanism of simple form and few parts to take the place of the conventional keyboard of typewriters and eliminate completely finger shifting from key to key in typing and other operations of the typewriter.

Another object is to provide mechanism of the character and for the purpose above set forth enabling resting of the hands while operating the mechanism and typewriter and so as to obviate muscular tension caused by suspension of the arms and hands necessary in operation of the conventional typewriter.

Still another object is to provide in operating the conventional typewriter for reducing to a minimum tiring elbow motion.

Still another object is to provide electromagnetic operating mechanism for a typewriter involving fewer electromagnets than other mechanisms designed for a similar purpose, and for otherwise simplifying such mechanisms and rendering the same inexpensive to install, manufacture and service.

Other and subordinate objects, within the purview of my invention, together with the precise nature of my improvements will be readily understood when the succeeding description and claims are read with reference to the drawings accompanying and forming part of this specification.

In said drawings:

Figure 1 is a view in side elevation, partly in section, illustrating my invention applied in the preferred embodiment thereof;

Figure 2 is a view in vertical transverse section taken on the line 2—2 of Figure 1;

Figure 3 is a view in front elevation of the slideable casing for the line of solenoids;

Figure 4 is a view in end elevation of the same;

Figure 5 is a view in front elevation of the slideable frame for the slideable casing and with solenoid parts carried thereby;

Figure 6 is a view in end elevation of the same;

Figure 7 is a view in end elevation of the fixed skeleton frame with the slideable frame therein and the slideable casing in the slideable frame with the solenoids for sliding said casing and slideable frame;

Figure 8 is a view in vertical transverse section taken on the line 8—8 of Figure 2;

Figure 9 is a view in side elevation, partly in section, of the selector viewed from the left-hand side thereof;

2

Figure 10 is a view in rear elevation of the selector;

Figure 11 is a view in front elevation of the same;

5 Figure 12 is a view in vertical transverse section taken on the line 12—12 of Figure 9;

Figure 13 is a fragmentary view in plan of the selector with the keeper ring for the parts of one of the push button switches removed to show the switch parts in the socket;

Figure 14 is a fragmentary view in transverse section taken on the line 14—14 of Figure 13;

Figure 15 is a diagrammatic view of the circuit;

15 Figure 16 is a diagrammatic view of the line of solenoids and the levers operated thereby designated in accordance with the operations effected in the typewriter by depression of the levers;

Figure 17 is a diagrammatic view of the left-hand push button switch carrier with the push buttons designated in accordance with the operations effected by closing of the push button switches in the different positions of the line of solenoids; and

25 Figure 18 is a similar view of the right-hand push button switch carrier.

Referring now to the drawings by numerals, and especially to Figures 1, 2 and 16, according to my invention, the conventional upstroke typewriter, shown generally as sufficient for the present purposes, and designated by the numeral 1, is operated through the medium of horizontal, deppressible levers 2 arranged in a series in side-by-side relation and corresponding to the usual

35 key levers of the typewriter, but with the key ends removed. The levers 2 of the series are operative, in a manner presently described, to effect the usual various operations in the typewriter. These levers 2, with the exception pres-

40 ently noted, are arranged substantially as in the conventional typewriter for operation to bring upper and lower case type, not shown, to the printing point, also numerals, punctuation and other symbols, and to back-space, effect the carriage return, margin release, and tabulation,

45 and have been designated in Figure 16 in accordance with the operations resulting in the typewriter from depression of each of said levers. The exception, previously noted, is that an intermediate lever 2 of the series effects letter spacing of the typewriter carriage, not shown, through the usual connections well understood in the art, and in the conventional typewriter

50 operated by the space bar, and a spare or dummy lever is provided in the series at the left end of the series, or left side of the typewriter 1,

for a purpose presently apparent. As will be noted upon reference particularly to Figure 16, there are forty-eight levers 2 in the series.

A series of twelve solenoids designated 3 are mounted, as presently described, vertically in side-by-side engagement, for compactness, to extend in a horizontal line across the series of levers 2 and with downwardly extending cores, or armatures, 4 adapted to be projected and to descend against said levers 2 when the solenoids 3 are energized.

The solenoids 3 are mounted in line in an elongated, rectangular, open bottom casing 5 extending endwise across the series of levers 2, horizontally, and endwise slidable from a normal position in horizontal guides 6 in a similarly shaped skeleton frame 7 endwise movable in the same direction as said casing 5 from a normal position and in horizontal guides 8 in an elongated, fixed skeleton frame 9 bolted, as at 10, at its ends to the side frame members 11 of the typewriter 1 to extend endwise across the series of levers 2.

In the normal position of the solenoids 3, the slidable casing 5 and the slidable frame 7, the cores 4 of the solenoids 3 are positioned to descend upon and operate the first lever of each successive group of four levers 2 in the series counting from the left-hand end of the series as illustrated in Figure 16. The slidable casing 5 is slidable from its normal position into a first advance position, in the slidable frame 7, to advance the line of solenoids 3 from normal position one step from left to right to position the cores 4 to descend upon and operate the second lever 2 in each successive group of four, as shown in dotted lines in Figure 16. The slidable frame 7 is slidable for advance from normal position twice as far the slidable frame 5 to advance the slidable casing 5 into a second advance position and advance the line of solenoids 3 a distance equal to two steps from normal position to position the cores 4 to descend upon and operate the third levers 2 in each of the designated groups of four, as shown in dotted lines in Figure 16. Conjoint sliding of the slidable casing 5 into its advance position in the sliding frame 7, and sliding of said frame 7 to further advance the slidable casing 5 will advance the line of solenoids 3 a distance equal to three steps of movement and thereby position the cores 4 for descent against and operation of the fourth levers 2 of each of the designated groups of four of such levers, also as shown in dotted lines in Figure 16. Thus, it will be seen that the line of twelve solenoids 3 is arranged to operate all forty-eight levers 2 of the series, each solenoid 3 operating four of said levers in a group selectively.

For sliding the slidable casing 5 in the slidable frame 7, said casing is provided at one end thereof with a horizontal core, or armature, 12 of a solenoid 13, the coil casing 14 of which is suitably secured, detachably, to the corresponding end of the slidable frame 7, said solenoid 13, when energized, serving to advance the slidable casing 5 in the slidable frame 7 in the manner described. A helical expansion spring 15 interposed on the core 12 between said corresponding ends of the slidable casing 5 and the slidable frame 7 yieldingly maintains said casing 5 and the solenoids 3 in normal position. Engagement of the opposite end of the slidable casing 5 with the corresponding end of the slidable frame 7 establishes the normal position of said casing 5 under the urge of the spring 15.

The slidable frame 7 is slid by a solenoid 16, like

the solenoid 13, and having a core, or armature, 17 suitably attached, horizontally, to one end of said frame 7 to be retracted when the solenoid 16 is energized into a coil casing 18 on the corresponding end of the fixed skeleton frame 9. A helical expansion spring 19 on said core 17 interposed between said corresponding ends of the slidable frame 7 and the fixed frame 9 yieldingly retains said frame 7 in normal position established by engagement of the opposite end of said frame 7 with the corresponding end of the fixed frame 9.

In front of the typewriter 1 is a cylindrical selector for selecting the levers 2 and which is designated as a unit by the numeral 20. The selector 20 comprises a cylindrical body 21 of a diameter and length suitable for grasping at both ends by the hands of an operator and which is formed with a central, circumferential flange 22. A bottom, radial stem 23 on the flange 22 is pivoted by a bolt 24 in a base member 25 adapted to be bolted, as at 26, to a typewriter desk 27, or the like, on which the typewriter 1 is disposed, so that said selector 20 is disposed in front of the typewriter 1 with its axis parallel with the front side of said typewriter, said selector 20 being swingable on the base member 25 rearwardly, away from the operator, for a purpose presently seen.

A pair of annular, flat, left and right hand push button switch carriers 28, 29 are rotatably fitted over opposite ends of the body 21 against the flange 22 and retained thereon by keeper disks 30 secured to the ends of said body 21 by axial screws 31. The push button switch carriers 28, 29 form therebetween a central, circumferential groove around said body 1, part way, for a purpose to be explained.

Push button switches for energizing the solenoids 3 are provided in the rear side of the selector 20, there being a left hand series of four of such switches 33 in the left hand switch carrier 28 for operation by the fingers of the left hand, and a similar series of such switches 34 in the right-hand switch carrier 29 for operation by the fingers of the right hand, all of said switches being spaced circumferentially on said carriers. At the front of the selector 20, the left and right hand switch carriers 28, 29 are each provided with a pair of left and right hand circumferentially spaced push button switches 35, 36 for operation by the thumbs of the right and left hands of the operator, respectively. These push button switches, see Figures 14 and 15, are of the usual type with a movable button pressed contact 37 for engaging a pair of fixed contacts 38 in opposition to a suitable spring 39 backing the push button 40, the switch parts being arranged in sockets 41 in said carriers 28, 29 and the movable parts of said switches being retained in the sockets by keeper rings, as at 42, threaded into said sockets.

Pairs of insulated leads 43, 44 connect the fixed contacts 38 of the push button switches in opposite sides 45, 46 of a suitable electric circuit with the solenoids 3 suitably interposed in the leads 44 and whereby the push button switches 33, 34, 35, 36 are connected in parallel in the circuit, also the solenoids 3. The leads 43, 44 extend out of said carriers 28, 29 into the before-mentioned groove 32 by way of side openings, as at 47, in said carriers and are encased in an insulated sheath 48 which extends to the top of the fixed skeleton frame 9. The leads 44 to the solenoids 3 extend out of said sheath 48 to said

solenoids 3 between a pair of horizontal top pinch bars 49 forming part of the fixed skeleton frame 9.

As will now be seen, each of the push button switches 33, 34, 35, 36 is designed, when closed by the push button 40, to effect, by energizing one of the solenoids 3, operation of each of four levers 2 of a group of four and in the described four different positions assumed by the line of solenoids 3 under step advance of the slidable casing 5 and the slidable frame 7, and whereby to effect either operation of printing characters, or symbols, to the printing point, not shown, of the typewriter 1, or operations such as back spacing, carriage return, margin release, tabulation, and/or letter spacing through operation of the appropriate mechanisms, not shown, of the typewriter and through the medium of the levers 2 which are operated.

For selection of the proper push button switches 33 to 36 to bring desired type to the printing point, or effect other machine operations, the push button switch carriers 28, 29, as illustrated diagrammatically in Figures 17 and 18, are marked, or otherwise designated, adjacent the push buttons 40 according to the operations which will be effected by depression of the push buttons 40 in each of the four described positions of the line of solenoids 3.

For energizing the solenoids 13 and 16, a pair of left and right hand knife switches 51, 52 are provided on the left and right hand sides of the selector 20 for closing, by slight rotation, clockwise as viewed in Figures 1 and 9, of the left and right hand switch carriers 28, 29. The switches 51, 52 each comprise a movable contact lug 53 on the switch carriers 28, 29, as the case may be, suitably insulated therefrom, as shown, and projecting into a peripheral end recess 54 in the body 21 of the selector 20 closed by the adjacent cap disks 30. Relatively fixed knife switch contacts 55 are provided for the contact lugs 53 of the recesses 54. The contacts 55 are connected in opposite sides 45, 46 of the circuit, in pairs, in parallel by leads 56, 57 with the solenoids 13, 16 interposed in the leads 57 for energizing by the left and right hand switches 51, 52, respectively. The leads 56, 57 are encased to the solenoids 13, 16 in insulation sheaths 58, 59 secured between the pinch bars 49. Suitable spring pressed balls, as at 60, 61, in the body 21 of the selector 20, retain the left and right hand switches 51, 52 open or closed. The sheaths 58, 59 extend into the sheath 48 to the fixed skeleton frame 9 and pass through the switch carriers 28, 29 by way of openings as at 62 in said carriers.

As will now be obvious, by rotating the left hand switch carrier 28 to close the left hand switch 51, the line of solenoids 3 is moved to advance the same from normal position, one step, by rotating the right hand switch carrier 29 to close the right hand switch 52, the line of solenoids 3 is moved to advance the same from normal position a distance corresponding to two steps, and by rotating both said switch carriers 28, 29, both said switches 51, 52 will be closed to move the line of solenoids 3 for advance a distance corresponding to three steps, or increments, of movement.

In addition to the foregoing, my invention includes a solenoid for effecting case shift in the typewriter 1, for instance, in the manner disclosed by U. S. Letters Patent No. 1,889,315. This solenoid, designated 65, and shown in Figure 15, is connected in the circuit by means of leads

66, 67 from opposite sides 45, 46 of the circuit and connected to opposite sides of the relatively fixed contacts 68 of a third knife-type switch 69, the solenoid 65 being interposed in the lead 67. The knife-type switch 69 is designed to be closed by swinging of the selector 20 on the bolt 24 away from the operator. To this end, the fixed contacts 68 of said switch 69 are suitably fixed in the base member 25 and insulated therefrom. A blade contact 70 extends laterally from the stem 23 and is suitably insulated therefrom, as at 71, the arrangement being such that upon swinging of the selector 20, as described, the blade contact 70 will descend between fixed contacts 68 and close said switch 69. A spring-pressed ball 72 in the base member 25 yieldingly retains the switch 69 open or closed. The leads 66, 67 extend through an insulated sheath 73. A stop 74 on the base member 25 engaged by the blade contact 70 limits swinging of the selector 20 back to normal position and establishes that position.

The manner in which the invention is used and operated will be readily understood from the foregoing and the following summarizing explanation. The selector 20 is grasped at its ends by both hands of the operator with the left hand loosely grasping the left hand switch carrier 28, and the right hand similarly grasping the right hand switch carrier 29, the fingers of the left hand being loosely placed against the push buttons 40 of the left hand series of finger operative push button switches 33 and the fingers of the right hand similarly positioned against the push buttons 40 of the right hand series of finger operative push button switches 34. The thumbs are held against said carriers for ready use on the push buttons 40 of the pairs of thumb operative push button switches 35, 36. The left and right hand switches 51, 52 for energizing the solenoids 13, 16 may be left open, or closed, by rotation of said carriers 28, 29, in the manner described, to either leave the line of solenoids 3 in normal position or advance said line so that levers 2 of the groups of four operative by the cores 4 may be selectively operated through finger operation of the push buttons 40 of selected switches of the series 33, 34, or thumb operation of the pairs of switches 35, 36 may be resorted to if required to operate levers 2. As will be clear, the line of solenoids 3 is left in normal position, or advanced according to the selected switches of the series 33, 34 or the pairs 35, 36 which it is desired to operate and said switches are selected in accordance with desired operation of the typewriter 1 whether typing in upper and lower case is desired, or other operations such as previously specified. The push buttons 40 obviously act as keys selected in accordance with the desired operation of the typewriter 1 and provide for obviating finger shifting from key to key and fatiguing suspension of the arms in typing. All fingers of both hands are permanently positioned for instant use without shifting the hands or fingers and the thumbs are advantageously used in a like manner.

The foregoing will, it is believed, suffice to impart a clear understanding of my invention without further explanation.

Manifestly, the invention, as described, is susceptible of modification without departing from the inventive concept, and right is herein reserved to such modifications as fall within the scope of the appended claims.

Having described the invention, what is claimed as new is as follows:

1. Operating mechanism for a typewriter comprising a series of levers adapted for operation to effect typing in said typewriter and other operations therein, solenoids for operating said levers less in number than said levers and movable relative to said series of levers in unison for selective operation to operate selected levers, means for moving said solenoids, means for operating said solenoids selectively, and a member for grasping by both hands and embodying manipulative controls for both said means.

2. Operating mechanism for a typewriter comprising a series of depressible levers adapted for operation to effect typing in the typewriter and other operations therein, means for operating said levers including a series of solenoids movable across said series of levers laterally thereof in unison for selective operation respectively of different levers in the series, a member remote from the typewriter for grasping by both hands, and means for moving said solenoids including manipulative control devices on said member.

3. Operating mechanism for a typewriter comprising a series of depressible levers adapted for operation to effect typing in the typewriter and other operations therein, a series of solenoids for operating said levers movable in unison across the series of levers laterally thereof for operation selectively to operate selected levers, electromagnetic means for moving said solenoids, and means for selectively operating said solenoids including a member remote from said typewriter for grasping by both hands and embodying finger and thumb operative push button control devices respectively.

4. Operating mechanism for a typewriter comprising a series of levers adapted for operation to effect typing in said typewriter and other operations therein, a series of solenoids less in number than said levers movable relative to said levers across the same in unison for selective operation to operate said levers selectively, a hand grip member separate from said typewriter for grasping by both hands, rotary devices on said member for rotation by the hands, key forming devices on said rotary devices, means to move said solenoids by rotation of said rotary devices, and means to operate said solenoids selectively under control of said key forming devices.

5. Apparatus for operating a typewriter comprising a series of side by side levers adapted for operation to effect typing in the typewriter and other operations therein, a series of solenoids of less number than said levers arranged in line and movable in line in unison across the series of levers into operative relation to different levers, a hand grip member separate from the typewriter adapted for grasping by both hands of an operator, electromagnetic means for variably moving said solenoids, an electric circuit for energizing said solenoids and in which said electromagnetic means is interposed, and manipulative devices on said member for controlling said circuit to energize said solenoids and said electromagnetic means selectively.

6. Apparatus for operating a typewriter comprising a series of side by side levers adapted for operation to effect typing in said typewriter and other operations therein, a series of solenoids of less number than said levers arranged in line and movable in line in unison across the series of levers into operative relation to different levers, a hand grip member separate from the typewriter

adapted for grasping by both hands of an operator, a pair of right and left hand rotary control devices on said hand grip member for operation by the right and left hands of the operator, and means for variably moving said solenoids controlled by rotation of said control devices.

7. Apparatus for operating a typewriter comprising a series of side by side levers adapted for operation to effect typing in said typewriter and other operations therein, a series of solenoids of less number than said levers arranged in line and movable in line in unison across the series of levers into operative relation to different levers, a hand grip member separate from the typewriter adapted for grasping by both hands of an operator, a pair of right and left hand rotary control members on said hand grip member for operation by the right and left hands of the operator, and means for variably moving said solenoids controlled by rotation of said control members singly and conjointly.

8. Apparatus for operating a typewriter comprising a series of side by side levers adapted for operation to effect typing in the typewriter and other operations therein, a series of solenoids of less number than said levers arranged in line and movable in line in unison across the series of levers into operative relation to different levers, a hand grip member separate from the typewriter adapted for grasping by both hands of an operator, a pair of annular right and left hand control members surrounding the hand grip member and rotatably mounted thereon for operation by the right and left hands of the operator grasping said hand grip member, and electromagnetic means for variably moving said solenoids controlled by rotation of said control members singly and conjointly.

9. Apparatus for operating a typewriter comprising a series of side by side levers adapted for operation to effect typing in said typewriter and other operations therein, a series of solenoids of less number than said levers arranged in line and movable in line in unison across the series of levers into operative relation to different levers, a casing for said solenoids, a frame in which said casing is slidably mounted for moving the solenoids in limited degree, said frame being slidably mounted to move said casing past its limit of movement, and electromagnetic means for sliding said casing and frame selectively.

10. Apparatus for operating a typewriter having case shift mechanism comprising a series of side by side levers adapted to operate said typewriter for typing, a series of solenoids of less number than said levers movable in unison into operative relation to different levers for operating the same, a hand grip member for grasping by the hands of an operator separate from said typewriter and swingably mounted, key forming devices on said member, means for energizing said solenoids selectively under control of said devices, a solenoid adapted for connection to said case shift mechanism, and means to energize said last-mentioned solenoid controlled by swinging of said hand grip member.

11. A remote control for a typewriter operating mechanism in which solenoids and electromagnetic means are interposed in an electric circuit, said control comprising a circular hand grip member, a pair of circular control devices rotatably mounted on opposite sides of said member for grasping and rotation by the right and left hands of an operator, contact elements on said mem-

ber and devices engaged by rotation of said devices singly and conjointly, selectively, and adapted for connection in said circuit to close circuit to the electromagnets singly and in unison, and push button switches on said devices for operation by the fingers and thumbs of the hands and adapted for connection in said circuit to close circuit to said solenoids singly.

12. A remote control for a typewriter operating mechanism in which electromagnets are interposed in an electric circuit, said controls comprising a circular hand grip member, a pair of circular control devices rotatably mounted on opposite sides of said member for grasping and rotation by the right and left hands of an operator, and contact elements on said member and devices engaged by rotation of said devices singly and conjointly, selectively, and adapted for connection in said circuit to close circuit to the electromagnets singly and in unison.

13. A remote control for typewriter operating mechanism in which solenoids are interposed in an electric circuit, said control comprising a circular hand grip member, a pair of circular control devices rotatably mounted on opposite sides of said member for grasping and rotation

by the right and left hands of an operator, and push button switches on said devices for operation by the fingers and thumbs of the hands and adapted for connection in said circuit to close circuit to said solenoids singly.

14. A remote control according to claim 13 wherein said push button switches are circumferentially spaced around said devices in spaced apart groups at diametrically opposite sides of said devices for positioning of the fingers and thumbs of the hands on the push buttons of the switches in the groups.

HERMAN JARMANN.
